MANUFACTURE OF JOURNAL BOXES

Harry O. Nekola, Cleveland Heights, Ohio, assignor to National Malleable and Steel Castings Company, Cleveland, Ohio, a corporation of Ohio

Application February 2, 1933, Serial No. 654,820

5 Claims. (Cl. 29—166)

This invention relates to improvements in the production of journal box hinge lugs particularly adapted to cooperate with a lid of the type including a spring urged lever which coacts with the outer nose of the lug to maintain the cover in closed as well as in open position. Such a lid construction is disclosed in my Patent No. 1,938,398 issued on December 5, 1933. The invention also relates to a novel method of reclaiming journal boxes having worn or otherwise unsuitable lugs and adapting them for proper cooperation with a lid of the type shown in my prior patent.

A type of journal box lug commonly employed in the past consists of spaced walls providing narrow bearings for a pin, between which bearings extends a hollow portion of the lug having a forward face against which the lever of the closing mechanism is adapted to bear to hold the lid closed. After such boxes have been in service over considerable periods, the repeated opening and closing of the lids and possibly the vibration of the parts has resulted in wearing away the bearings to such an extent that the pins do not occupy their proper positions; at the same time the faces of the hollow portions between the bearings have been worn away, in some instances even to the extent of exposing the interior of the lug. This has resulted in inferior operation of the older types of lids, and has proved especially troublesome when a lid in accordance with my copending application is applied to such a box. Due to the defective lug, it has been found, this type of lid does not remain tightly closed, and in some cases cannot be readily opened.

An object of the present invention is accordingly to provide for manufacturing or reconditioning journal box lugs in a simple and efficient manner to produce a lug which is superior to those previously employed and particularly suited for use in combination with lids of the type described in my prior patent. Other objects and advantages of the invention will be in part pointed out and in part apparent from the detailed description which will follow.

In order to illustrate one manner of carrying out the invention reference will be had to the accompanying drawings, wherein:

Fig. 1 is a vertical section, partly broken away through a journal box having the original lug and the type of lid disclosed in the patent referred to.

Fig. 2 is a front elevation, partly broken away, of the construction shown in Fig. 1 with the lid removed.

Fig. 3 is a central, vertical section through a typical lug, worn away through service.

Fig. 4 is a front elevation of the journal box lug shown in Fig. 3.

Fig. 5 is a perspective view of a journal box lug after the worn, central part has been cut away in accordance with the present invention.

Fig. 6 is a front elevation, partly broken away, of a journal box, showing my improved type of lug and a member for positioning and supporting the central portion of the lug during assembly.

Fig. 7 is a section, taken on the line 7—7 of Fig. 6, and showing a clamp for holding said member and the central portion of the lug in proper position while the portions of the lug are secured together.

Fig. 8 is a perspective view of an improved lug member in accordance with the invention, and

Fig. 9 is a perspective view of the completed lug and the adjacent portion of a journal box.

Referring first to Figs. 1 and 2, there is shown a journal box A having the usual or standard American Railway Association hinge lug 2 comprising spaced bearing portions 3 for pin 4 and central portion 5 having a generally vertical front face 6 and a generally horizontal top face 7 converging to form a nose 8. In older boxes of the type illustrated the lug is largely hollow and the pin 4 has its bearing in the relatively thin walls 30 at the outer ends of the portions 3.

The box is shown provided with a lid B of the type described in my prior patent referred to. It is preferably a two-part construction including a closure member 9 adapted to abut at its upper and lower portions and along its sides against the upper surface 10 and the other surfaces 11 surrounding and forming the mouth 12 of the journal box. The lid B also preferably includes a housing member 13 having portions 14 for engaging over the ends of pin 4 and thus pivotally supporting the member. As shown in my prior patent the lower end of member 13 is pivotally interlocked with a portion of the closure 9. At an intermediate point 16 the housing member is formed to provide a fulcrum for a two-armed lever 17. The upper arm 18 of the lever 17 is adapted to abut against the face 6 of the lug when the lid is in closed position, and against the face 7 when the lid is open, as shown in dotted lines in Figure 1, while the lower arm 19 is adapted to be urged outwardly from the mouth of the box by a coil spring (not shown) operatively interposed under compression between the lower end of arm 19 and the closure member 9. Such a

member is formed to provide a fulcrum for a two-armed lever 17. The upper arm 18 of the lever 17 is adapted to abut against the face 6 of the lug when the lid is in closed position, and against the face 7 when the lid is open, as shown in dotted lines in Figure 1, while the lower arm 19 is adapted to be urged outwardly from the mouth of the box by a coil spring (not shown) operatively interposed under compression between the lower end of arm 19 and the closure member 9. Such a

spring is shown in my prior patent referred to. As made clear in my prior patent the spring is adapted to urge the upper end 18 of the lever 17 against the surface 6 of the lug so that the reaction will serve to maintain the lid in closed position. When the lid is opened the portion 18 rides over the nose 8 and bears against face 7, at which time the reaction is such as to maintain the lid in open position. The lever 17 is preferably of such width at its upper end as to bear only upon the central portion 5 of the lug and not upon the portions 3 of the lug.

When a journal box of the type illustrated is first put into service it is provided with circular openings 23, indicated in dot and dash lines in Figure 3, in the portions 3 at either end of the lug for receiving and supporting the pivot pin 4. After the lug has been in service for extended periods, repeated opening and closing of the lid, and possibly vibration of the structure, results in wearing away the bearing surfaces of the openings 23 so that they are considerably enlarged, for instance to the extent indicated in full lines at 24. Furthermore, the surfaces 6 and 7 adjacent the nose 8, as well as the nose itself, become worn away, often until there is a clear opening into the interior of the lug, as shown at 25 in Figs. 3 and 4, between front and top portions 26 and 27, respectively, of the lug. When an improved lid of the type described in my prior patent is placed on a box having the lug worn away, in somewhat the manner indicated, it has been found that the operation of the lid is impaired. More specifically, it is often difficult to open the lid, apparently due to the end 18 of the lever becoming caught in the worn portion of the lug, and moreover the lid does not under these conditions, tightly close the mouth of the journal box. Large numbers of such partially worn journal boxes are in service, and they are still capable of considerable further use except for the worn condition of the hinge lugs. In order to satisfactorily employ a closure on these boxes, and particularly my improved lid, it is necessary or highly desirable to provide a new lug on the box in accordance with the present invention. This effects considerable saving since it avoids discarding many old boxes which would otherwise be substantially useless. The saving is particularly great where the journal boxes are formed integral with the side frame of a car truck, as is often the case. Furthermore, this invention enables the modification or replacement of certain types of journal box lugs, which do not conform to standard American Railway Association specifications, and which are not adapted, without such change, to support my improved lid.

I shall now describe my simple, inexpensive and effective method of manufacturing, modifying or reconstructing journal boxes to provide them with improved lugs particularly adapted for cooperation with my improved lid.

In reconstructing a worn journal box lug, the central portion 5 of the lug may be cut away as shown in Fig. 4 along the lines a, b and c. This may be accomplished by an acetylene torch, or this portion of the casting may be removed in any other convenient manner. The portions of the lug remaining after this operation are illustrated in Fig. 5.

Within the cut-away portion there may then be inserted a member 30 of suitable shape having front face 6', top face 7' and nose 8', as shown in Figs. 6, 7, 8 and 9. This member 30 may be

formed of any suitable material which is preferably, although not necessarily, superior in wear-resisting properties to the metal of which the casting including lug portions 3 is formed. For instance, it may be formed or forged or open hearth steel, or as a casting of a highly wear-resistant steel, or the like, depending upon the wear-resistant properties desired. The width of the member is such that it is adapted to be interposed between the lug portions 3, with its ends adjacent the inner faces of said portions. The member 30 is formed with an opening 31 of such size as to receive and form a suitable bearing for a pivot pin of normal or standard size; it is preferably of the same diameter as the openings in standard A. R. A. lugs.

The member 30 is preferably welded to the portions 3 of the lug, and it is desirable to provide for supporting the member in convenient manner upon the journal box during the welding operation. This is particularly important where the box is formed integral with the side frame. For this purpose, I have devised a supporting member or tool which may comprise an arm 32 adapted to lie over the mouth of the box and rest upon the upper and lower surfaces 10 and 11. Secured to the arm 32, or formed integral therewith, is a transverse arm 33 having fingers 34 bent rearwardly at an angle of slightly less than 90° and adapted to rest upon the upper surface 35 of the top of the journal box at either side of the lug portions 3, as best shown in Fig. 6. The upper end of the arm 32, above the arm 33, may be provided with portions or fingers 36 turned inwardly toward the rear of the box and adapted to underlie the member 30 to support it at the desired height. A central portion 37 of the upper end of arm 33, between portions 36, may extend substantially vertically or about at right angles to the portions 36, and is adapted to abut against the front face 6' of member 30 in order to position it in proper relation to the mouth of the box. For holding the member 30 in place against the rear surface of portion 37, a screw clamp 38 may be employed, as shown in Fig. 7. No special means need be employed for holding the supporting device against the box, since the mouth of the box is inclined and the weight of the device is sufficient to hold it properly against this inclined face. As indicated, the member 30 is preferably supported so that the center line of the opening 31 is aligned with the normal centers of the openings 23 in the hinge lug as initially manufactured. Through the arrangement just described, the positioning and supporting of the member 30 may be accomplished in a rapid and facile manner, by simply putting the tool in place and suitably holding the member 30 on the tool. By constructing the fingers 34 and 36 parallel and generally straight, provision is made for withdrawing the tool after the member 30 is secured in place.

In securing the member 30 to the lug portions 3, it is preferable, as mentioned, to weld the parts together. Where a weld is to be employed for this purpose, it is desirable to bevel or chamfer the edges of the member 30, as shown at 40. Welding material may be applied at suitable points preferably at the top and rear at both ends of the member 30, as shown at 41 and 42. However, if desired, the parts may be welded together around any convenient portion of the perimeter of the member 30, or a continuous weld may be employed. While this affords an extremely simple manner of providing a sturdy connection be-

tween the portions of the lug, it will be understood that other practical ways of securing the member 30 may be employed.

Through the present invention, there is provided a superior bearing surface for the hinge pin, inasmuch as the pin bears on the wall of the opening 31 throughout the entire length of the member 30, whereas in prior constructions, the bearings for the pin are merely the relatively thin wall portions at either end of the lug, as best shown in Fig. 5. Furthermore, by reason of the improved construction of the lug, particularly when member 30 is formed, as is preferable, of relatively wear-resistant material as compared to usual hinge lugs, the wearing away of the surfaces against which the lever arm 18 bears, may be reduced to a minimum. Moreover, the construction is exceptionally sturdy and durable and, particularly in combination with my improved lid, gives excellent results. The operations are simple to carry out, and may be performed without disassembling the journal boxes from the car trucks.

While my invention has been described in connection with a particular type of lid with which it is of special value, it will be understood that it may be used also in relation to other types of lids. Furthermore while the invention has been explained with reference to the modification of old journal box lugs the advantage of applying a special, preformed lug of good, wear resisting qualities might be utilized even in connection with new boxes.

The terms and expressions which I have employed are used as terms of description and not of limitation, and I have no intention, in the use of such terms and expressions, of excluding any equivalents of the features shown and described, or portions thereof, but recognize that various modifications are possible within the scope of the invention claimed.

I claim:

1. A method of reconstructing a journal box hinge lug, which comprises burning out the cen-

tral portion of the hinge lug casting to provide spaced side portions, supporting on said box a preformed member fitting freely between said side portions with front and top bearing surfaces properly positioned with reference to fixed surfaces on the box, and uniting said member with said spaced portions. 5

2. A method of reclaiming a worn journal box hinge lug which comprises cutting away the center portion of a worn hinge lug, supporting on said box an apertured, preformed member fitting freely between the remaining portions of said lug with its aperture substantially aligned with the original lug aperture, and welding the member to said portions. 15

3. A method of forming an improved A. R. A. standard journal box hinge lug which comprises cutting away the central portion of a hinge lug, on an existing box, engaging a supporting member over the mouth of the journal box, positioning an apertured, preformed lug member on said supporting member freely between the remaining portions of the original lug, and welding said last-named member to said portions. 20

4. A method of reclaiming a worn journal box hinge lug which comprises cutting away the center portion of a worn hinge lug to leave two up-standing apertured ears, supporting on said box a preformed lug member fitting freely between said ears with its front and bottom faces in predetermined relation to the mouth of the box, and uniting said member with said ears. 25 30

5. A method of reclaiming a worn journal box hinge lug which comprises cutting away the center portion of a worn hinge lug to leave two up-standing apertured ears, supporting on said box a preformed lug member fitting freely between said ears with its bottom face at a predetermined distance above the top of the box mouth and its front face in predetermined relation to the plane of the box mouth, and uniting said member with said ears. 35 40

HARRY O. NEKOLA.
